UNITED STATES PATENT OFFICE

162,984

APRON

Minnie Porter, Knoxville, Tenn.

Application April 19, 1950, Serial No. 9,344

Term of patent 14 years

(Cl. D3—26)

To all whom it may concern:

Be it known that I, Minnie Porter, a citizen of the United States, residing at Knoxville, Tennessee, have invented a new, original, and ornamental Design for an Apron, of which the following is a specification, reference being had to the accompanying drawing, forming part thereof.

In this showing:

Fig. 1 is a front view of the apron as it is worn, while

Fig. 2 is the corresponding back or rear view of the apron.

I claim:

The ornamental design for an apron, as shown.

MINNIE PORTER.
